UNITED STATES PATENT OFFICE.

LAYTON M. PARKHURST, OF INDIANAPOLIS, INDIANA, ASSIGNOR, BY DIRECT AND MESNE ASSIGNMENTS, OF ONE-HALF TO W. H. COOLEY, OF BUFFALO, NEW YORK, AND ONE-HALF TO RALPH G. LOCKWOOD AND VIRGIL H. LOCKWOOD, OF INDIANAPOLIS, INDIANA.

SAFETY-DEPOSITING MACHINE.

Application filed December 29, 1921, Serial No. 525,567. Renewed September 7, 1926.

The object of this invention is to provide a machine which may be located at any desired place for receiving savings deposits. Such machine is adapted to be located in factories, schools and other buildings for receiving and crediting small saving deposits.

Another object of the invention is to provide a series of holding members movable and slotted so as to receive a coin and discharge a savings deposit book or a receipt, stamp or the like, the means for causing the movement of said members to and from the operating position being provided with a locking means in connection with the holding members for locking the actuating means, excepting when released by the coin inserted in the holding member.

Another object of the invention is to provide a deposit machine of novel construction capable of maintaining the coins deposited in it in such relation that when the machine or the coin receiving receptacles are taken to the savings bank and opened, each depositor of a false coin or substitute coin can be identified, thereby avoiding losses to the bank.

Another object of the invention is to provide a machine of this character of relatively simple construction.

Other objects of the invention will be apparent to those skilled in the art to which my invention relates from the following description taken in connection with the accompanying drawings, wherein I have for illustrative purposes shown one embodiment of the invention.

In the drawings, Fig. 1 is a perspective view of the machine, embodying my invention.

Fig. 2 is a section on the line 2—2 of Fig. 1.

Fig. 3 is a section on the line 3—3 of Fig. 2.

Fig. 4 is a section on the line 4—4 of Fig. 2.

Fig. 5 is a section on the line 5—5 of Fig. 4.

Fig. 6 is a view similar to Fig. 5, but showing the discharge of a receipt.

Fig. 7 is a section on the line 7—7 of Fig. 4.

Fig. 8 is a view similar to Fig. 7, with a coin inserted.

Fig. 9 is a vertical longitudinal section

through a holding member for pass books.

Fig. 10 is a section on the line 10—10 of Fig. 2.

In detail the drawings herein show a frame or casing member 10 mounted upon a stand 11. The frame 10 has a hinged door 12 at the back which is adapted to be locked. On the inner surface of the bottom and top of the frame 10 there are suitable guides 14 extending from front to the rear for receiving guiding and holding a number of units or independent savings deposit and crediting devices. Thus in one frame there would be, as indicated in Figs. 1 and 2, one of said machines or units for delivering deposit books and another machine for receiving coins and delivering stamped receipts for twenty-five cent deposits, another for ten cent deposits and another for five cent deposits or any other denomination. There can be as many of these units as desired. All of the units are alike excepting variation in the adjustments of the coin slots therein for different denominations of coins to be inserted.

Referring to each unit or independent device for receiving and crediting savings deposits, there is a casing 20 preferably of rectangular shape in cross section and with a depth, that is, from front to back dimension considerably greater than its width or thickness, and one side, here the right-hand side of said casing, Fig. 3, forms a door 21, it being hinged to the main part of the casing 20 at the bottom and at the top the door is locked or otherwise secured. The front wall of the casing has a coin slot 25 varying in size according to the coin desired to be inserted, as shown in Fig. 1. Near the lower part of the front door of the casing there is a concave portion which has in it a vertical slot 27 through which a lever 28 operates vertically. Within the casing there is movably mounted series of holding members 30 preferably connected to and in fact forming a part of an endless chain, the inner ends of said members being pivoted to and between the ends of a pair of chain links 31, as shown. The endless chain is mounted at each end upon a pair of sprocket wheels 32 and 33. The latter sprocket wheel 33 is mounted loosely upon a spindle 34 which extends transversely of and is mounted and secured in the casing. A portion 35

105

100

105

of the casing is depressed and through it the spindle 34 extends for engagement with a nut 36 which serves to rigidly secure the spindle to the casing side wall. By preference I provide a spacing sleeve or washer 37 between the sprocket wheel and the depressed portion 35 of the casing. A collar 38 lies on the other side of the sprocket wheel and is secured to said spindle by a pin. The other end of the spindle has a reduced end adapted to fit snugly in a corresponding hole in the door 21 of the casing, such arrangement serving to hold the cover in proper position when it is closed.

At the lower end of the device the sprocket wheel 32 is mounted in a somewhat similar manner excepting that the spindle 34' is surrounded by a tubular shaft 40 and said tubular shaft is surrounded by a spacing sleeve or washer 41 which is secured to the sprocket wheel by bolts 42.

The lower sprocket wheel 32 is actuated by the lever 28 through the following means: At its inner end said lever is secured to the tubular shaft 40 and it carries a headed pin 43 which projects through a slot 44 in a sliding pawl 45 which is actuated inwardly by a spring 46 mounted on a pin on an arm 47 from the lever 28 and said spring tends to force the pawl inwardly and cause it to engage a ratchet wheel 50 which is secured to the inside of the sprocket wheel 32 and thus when the lever 28 is depressed, it will actuate said sprocket wheel and move it in the direction of the arrow A and thereby move the series of holding members 30 one step, or a distance equal to the distance between the coin receiving spaces of adjoining holding members 30.

The handle 28 after depression and operation as explained, is elevated or returned by a spring 51 which is at one end secured to an ear 52 connected with the handle and at the other end is fastened to a bracket 53 extending inward from the side of the casing 20.

As the handle returns or moves upward, the inclined inner end of the pawl 45 rides back over the teeth of the ratchet wheel 50 and during such return movement of said lever it causes the movement of a cam wheel 55 in a direction opposite to the former movement of the ratchet wheel 50. To do this said cam wheel 55 is loosely mounted on the spindle 34' and has a ratchet 56 engaging the ratchet at the end of the tubular shaft 40. Thus the return movement of the lever causes the return movement of the tubular shaft 40 and that, through the ratchet 56, moves the cam wheel 55, and such movement of the cam wheel elevates a bar 60 which carries a roller 61 on its lower end that rides on the cam wheel 55. The bar 60 is held and guided by guide 62 and at its upper end it is pivoted by a pin 63 to

the short arm of a bell crank lever 64 which is fulcrumed on the bracket 53. Therefore, the upward movement of the bar 60 will cause the movement of the upper end of the lever 64 to the left. The upper end of said lever 64 has a slot 65 through which pins 66 from a push rod 67 project. Said push rod is mounted in and guided by a block 68 secured to the casing and the function and purpose of this push rod will be hereafter explained.

The push rod is preferably square in cross section to keep it from turning and when actuated, it is adapted to deliver a receipt card or stamp 100 from the holding member which happens to be located opposite to it and it may be added that said push rod 67 is in alignment with the coin slot 25. Therefore, when the push rod is actuated, it will enter the holding member and push out of the holding member a deposit book or receipt card or stamp or other like thing which may have been placed in said holding member for the purpose of being discharged by the action of said push rod.

The machinery heretofore described is, however, locked from action until a coin of the proper value has been introduced through the coin slot 25 and the locking is effected by the following means: In each holding member 30 there is a horizontal slot 71 in the outer end thereof and in position to receive the coin as it enters the coin slot 25 in the casing. Into the side of said slot 71 an arm 72 projects horizontally from a locking lever 73 which extends downward therefrom and is fulcrumed on a pin 74' fastened in the casing. There is a laterally projecting pin 74 adapted to enter a hole 75 in the arm 47 from the lever 28. Therefore, when said pin 74 is projecting into said hole 75, said hand lever 28 cannot be operated. However, when a coin is inserted through the slot 25 and into the slot 71 of the holding member 30, it engages the arm 72 of lever 73 and actuates said lever so as to disengage the pin 74 from the hand lever 28 and thus permit the latter's operation. A spring 76, coiled around the fulcrum 74', projects upward and engages said lever and returns the lever to its normal and locking position and holds it in that position. The arm 47 on the hand lever 28, has a portion, 80, formed into a cam surface, (see Fig. 10) which as said lever is depressed, continues to engage the pin 74 and hold the lever 73 in its actuated position and thus keep the arm 72 at the upper end of said lever disengaged from the chain or series of holding members 30 until after the hand lever 28 has returned to its upper and normal position.

In the operation of the device the down stroke of the hand lever 28, after the coin has been inserted in the holding member which had been previously held by the lock-

ing bar 73, causes a forward or feeding movement of the whole series of holding members one step, and then on a return movement of the hand lever 28, the push rod 67 discharges a receipt stamp or the like from the slot of the holding member which was moved down into alignment with the discharging push rod by the immediately preceding downward movement of the hand lever 28.

10 Therefore, the receipt stamp 100 and the coin are not in a slot at the same time. The stamp is discharged before another coin is inserted or rather in one operation of the machine, the coin is inserted in one holding member and the stamp is discharged from the next holding member and the last holding member remains in registry with the coin receiving slot 25 until the next operation of the machine and, therefore, the slot 20 in the holding member is free to receive the coin.

The arrangement of the holding member for the pass books, or the series at the right hand side of the device, as shown in Fig. 1, 25 is somewhat different from the arrangement of the mechanism for discharging receipt stamps because in case of the pass books the holding member is provided with an extra slot 101 which is wide enough to receive 30 and hold a pass book 102. This arrangement is shown in Fig. 9, where the pass book slot is below the coin slot and in this form the arm or projection 72 of the locking lever 73 enters the coin slot as hereinbefore described, while the push rod 67 enters 35 the pass book slot and discharges the pass book. The invention is not limited to this mode of supplying pass books however.

The outer faces of the compartments or 40 holding members 30 always remain adjacent or close to the sides and bottom of the casing so that a coin inserted in the slot 71 will remain in the same slot during the subsequent operation of the machine and when 45 the machine is taken to the savings bank and opened, every coin will be in the holding member in which it was originally inserted. By numbering the holding members according to the deposit books or stamp receipts 50 in them to be delivered, the account in connection with which a false coin has been deposited can thus be identified and the bank or savings company protect itself and be able to charge up the false coin to the proper 55 account, whenever the deposit book is presented to the bank by the holder thereof.

What I claim is:

1. A machine for depositing and crediting savings deposits including a vertically disposed casing having a coin slot therein, a sprocket wheel mounted within each end of the casing, an endless chain mounted on said sprocket wheels, and having secured thereto a series of holding members with 60 slots opening outward and adapted to register with the coin slot in the casing and arranged

65 ter with the coin slot in the casing and said holding members being movable at all times adjacent to the casing so that each coin introduced will remain in the slot originally receiving it, means for actuating said series 70 of holders, and means for locking the same which is adapted to be released by the insertion of the coin.

2. A machine for depositing and crediting savings deposits including a vertically disposed casing having a horizontal coin slot therein, a sprocket wheel mounted within each end of the casing, an endless chain mounted on said sprocket wheels and having secured thereto a series of holding members 75 with horizontal slots opening outward and adapted to register with the coin slot in the casing and said holding members being movable at all times adjacent to the casing so that each coin introduced will remain in the slot originally receiving it, a hand lever adapted to actuate said sprocket wheels and projecting outward beyond said casing, and means normally locking the actuating lever and chain, said means being releasable upon the insertion of a coin.

3. A machine for depositing and crediting savings deposits including a vertically disposed casing having a horizontal coin slot therein, a sprocket wheel mounted within each end of the casing, an endless chain mounted on said sprocket wheels and having secured thereto a series of holding members 80 with horizontal slots opening outward and adapted to register with the coin slot in the casing and said holding members being movable at all times adjacent to the casing so that each coin introduced will remain in the slot originally receiving it, a hand lever adapted to actuate said sprocket wheels and projecting outward beyond said casing, and means normally locking the actuating lever, said means being releasable upon the insertion of a coin, and a spring for returning said locking means to a locking position.

4. A machine for depositing and crediting savings deposits including a vertically disposed casing having a horizontal coin slot therein, a sprocket wheel mounted within each end of the casing, an endless chain mounted on said sprocket wheels and having secured thereto a series of holding members 85 with horizontal slots opening outward and adapted to register with the coin slot in the casing and said holding members being movable at all times adjacent to the casing so that each coin introduced will remain in the slot originally receiving it, a hand lever adapted to actuate said sprocket wheels and projecting outward beyond said casing, a locking lever fulcrumed between its ends to said casing on the inside and provided at one end with an extension adapted to enter the slot in the holding member in registry with the coin slot in the casing and arranged

so that it will be forced out of said slot by the introduction of a coin, and a pin on the other end of said locking member adapted to engage a recess in said actuating lever when the locking lever is in locking position and to be disengaged from said lever when the locking lever is not in locking position.

5. A machine for depositing and crediting savings deposits including a vertically disposed casing having a horizontal coin slot therein, a sprocket wheel mounted within each end of the casing, an endless chain mounted on said sprocket wheels and having secured thereto a series of holding members with horizontal slots opening outward and adapted to register with the coin slot in the casing and said holding members being movable at all times adjacent to the casing so that each coin introduced will remain in the slot originally receiving it, a lever for actuating one of said sprocket wheels projecting outward beyond the casing, an arm extending from said lever within the casing and which is formed so as to have a cam surface, a locking lever fulcrumed to the casing and provided with a projection on one end to enter a slot in the holding member which is in registry with a coin slot in the casing so that it will be forced out of said slot by the insertion of a coin, and a pin on the other end of said locking member for entering a hole in the arm of said actuating member and arranged so that when the locking lever is moved to an unlocking position the movement of the actuating lever will cause said cam surface to move said locking member entirely out of engagement with said holding members so that they may be moved by the actuating member.

40 6. A machine for depositing and crediting savings deposits including a vertically disposed casing having a horizontal coin slot therein, a sprocket wheel mounted within each end of the casing, an endless chain mounted on said sprocket wheels and having secured thereto a series of holding members with horizontal slots opening outward and adapted to register with the coin slot in the casing and said holding members being movable at all times adjacent to the casing so that each coin introduced will remain in the slot originally receiving it, a lever projecting beyond the casing for actuating one of said sprocket wheels when the lever is depressed, means for locking the actuating lever, said means being releasable upon the insertion of a coin, and means for discharging the contents of a holding member during the return movement of the actuating member.

65 7. A machine for depositing and crediting savings deposits including a vertically disposed casing having a horizontal coin slot therein, a sprocket wheel mounted within each end of the casing, an endless chain mounted on said sprocket wheels and hav-

ing secured thereto a series of holding members with horizontal slots opening outward and adapted to register with the coin slot in the casing and said holding members being movable at all times adjacent to the casing so that each coin introduced will remain in the slot originally receiving it, a lever projecting beyond the casing for actuating one of said sprocket wheels when the lever is depressed, means for locking the actuating lever, said means being releasable upon the insertion of a coin, a plunger for discharging the contents of the holding member, means operable on the return movement of said actuating lever for actuating said discharging means, and a spring for returning said actuating means.

8. A machine for depositing coins including a casing having a coin inlet slot therein, movable coin holding means within said casing having a numbered series of coin receiving slots therein adapted to successively register with the coin inlet slot of the casing and keep the coins separate from each other, means for locking the coin holding means from movement and adapted to be released by the introduction of a coin into one of said coin receiving slots, and means operable after the release of said coin locking means for moving the coin holding means to bring another coin receiving slot therein into registry with the coin inlet slot of the casing.

9. A machine for depositing and crediting savings deposits including a casing having a coin slot therein, movable coin holding means within said casing having a numbered series of slots therein adapted to alternately hold a receipt and receive a coin, means to advance said coin holding means, means for locking said holding means from movement and adapted to be released by the introduction of a coin, and means operable after the release of said locking means for discharging a receipt from the next succeeding holding member.

10. A machine for depositing and crediting savings deposits including a casing having a coin slot therein, a series of holding members movable within said casing successively into registry with said coin slot and each member having a slot for alternately holding a receipt and for receiving a coin, means to advance said holding members, means for locking said holding members against movement and arranged so as to be released by the introduction of the coin into a holding member, and means operable after the release of said locking means for discharging a receipt from the next succeeding holding member.

11. A machine for depositing and crediting savings deposits including a casing having a coin slot therein, a series of holding members movable within said casing successively into registry with said coin slot and

- each member having a slot for alternately holding a receipt and for receiving a coin, and each of the holding members in said series being numbered in succession whereby they can be identified, means to advance said holding members, means for locking said holding members against movement and arranged so as to be released by the introduction of a coin into a holding member, and means operable after the release of said locking means for discharging a receipt from the next succeeding holding member.
12. A machine for depositing and crediting savings deposits including a casing, a series of holding members within said casing, each member having a slot for alternately holding a receipt and receiving a coin, means to advance said holding members, means for locking said holding members arranged so as to be released by the introduction of a coin into a holding member, and means operable after the release of said locking means for discharging a receipt from the next succeeding holding member.
13. A machine for receiving savings deposits including a casing having a coin slot therein, a series of holding members movable within said casing successively into registry with said coin slot, each said member having a chamber for alternately holding a receipt and for receiving a coin, means for locking said holding members against movement and arranged so as to be released by the introduction of the coin into a holding member, and means operable after the in-
- sertion of a coin and the release of said locking means for first moving the holders to position the chamber of the holder receiving the coin out of registry with said coin slot and position the chamber of the succeeding holder in registry therewith and then discharging a receipt from the chamber of said last mentioned holder through said slot.
14. In a machine for receiving savings deposits, the combination of a casing having a coin slot formed in one wall thereof, a series of members movable within said casing and arranged successively to register with said coin slot, each said holder carrying an identification mark and formed with a chamber adapted to receive a check, stamp or ticket bearing an identification mark, means for locking said series of members against movement, said locking means being arranged to be released upon the introduction of a coin through said slot into the chamber of a holding member in registry therewith, and means operable after the release of said locking means for first moving the holders to position the chamber of the holder receiving the coin out of registry with said coin slot and to position the chamber of the succeeding holder in registry therewith and for then discharging a check, stamp or ticket from the chamber of said last mentioned holder through said slot.

In testimony whereof, I hereunto affix my signature.

LAYTON M. PARKHURST.
